UNITED STATES PATENT OFFICE

172,974

LINK BAND FOR A WATCH OR SIMILAR ARTICLE

Isidore Kaplan, New York, N. Y.

Application March 12, 1954, Serial No. 29,484

Term of patent 7 years

(Cl. D45—4)

To all whom it may concern:

Be it known that I, Isidore Kaplan, a citizen of the United States of America and a resident of the city of New York, county of Bronx, and State of New York, have invented a new, original, and ornamental Design for a Link Band for a Watch or Similar Article, of which the following is a specification, reference being had to the accompanying drawing, forming a part hereof, wherein:

Fig. 1 is a top plan view of a link band for a watch or similar article, showing my new design;

Fig. 2 is an edge view of the same; and

Fig. 3 is a bottom plan view of the same.

The dominant features of my design reside in those portions shown in full lines; the links shown in full lines being repeated on both sides of the clasp, as indicated by broken lines.

I claim:

The ornamental design for a link band for a watch or similar article, substantially as shown and described.
